(57) **CLAIM**

I claim the ornamental design for an automatic parking ticket dispenser and calculator, as shown and described.

DESCRIPTION

FIG. 1 is a perspective view of an automatic parking ticket dispenser and calculator according to my new design;

FIG. 2 is a front view of the automatic parking ticket dispenser and calculator of FIG. 1;

FIG. 3 is a left side view of the automatic parking ticket dispenser and calculator of FIG. 1, which is a mirror image of the right side view of the automatic parking ticket dispenser and calculator of FIG. 1; and,

FIG. 4 is a rear view of the automatic parking ticket dispenser and calculator of FIG. 1.

The top and bottom surfaces of the automatic parking ticket dispenser and calculator are flat and/or devoid of surface ornamentation.

In the drawings, the broken lines are for illustrative purposes only and form no part of the claimed design.
